APPARATUS FOR FORMING SMOOTHLY
ROUNDED CAN BODIESFrank Krueger, Brooklyn, N. Y., assignor to E. W.
Bliss Company, Brooklyn, N. Y., a corporation
of Delaware

Application January 9, 1933, Serial No. 650,780

10 Claims. (Cl. 153—32)

In my application Serial No. 628,339, filed August 11, 1932, (patented October 17, 1933, No. 1,930,562) I have set forth a method of smoothly rounding can bodies to remove irregularities or flat portions therefrom by a circumferential rolling of the body to impart successive and alternate wave bending to its sheet metal wall, the alternate wave bends being carried beyond the elastic limit of the metal. In said application I have also set forth an apparatus for accomplishing such wave bending, said apparatus comprising a single unit adapted to operate upon only one can body at a time.

The present invention provides an improved apparatus for practicing the said method expeditiously and economically, by the provision of multiple units operating simultaneously on a plurality of can bodies. The machine constituting the preferred embodiment of the invention is adapted for continuous operation, receiving a continuous stream of successive can bodies, applying them between the wave bending rolls or surfaces, effecting the wave bending and subsequent milder rolling for effacing the residual wave bends and removing the can body from between the rolling surfaces and finally ejecting the successive bodies thus treated from the machine.

The machine in its preferred embodiment is illustrated in the accompanying drawings, where-

53 in—

Fig. 1 is a perspective view of the machine.

Fig. 2 is a longitudinal, vertical section.

Fig. 3 is a transverse section on a larger scale than Fig. 2, the plane of the section being indicated by the line 3—3 in Fig. 2.

Fig. 4 is a vertical transverse section on the same scale as Fig. 3, the plane of the section being indicated on the line 4—4 in Fig. 2.

Fig. 5 is a fragmentary longitudinal section illustrating the means for feeding the can bodies to or from the wave bending position, the plane of the section being on the line 5—5 in Figs. 3 and 4.

Fig. 6 is a fragmentary longitudinal section of the means for advancing the wave bending rolls, the plane of the section being on the line 6—6 in Figs. 3 and 4.

Fig. 7 is an elevation of the movable parts shown in Fig. 6, viewed in the direction of the arrow 7 therein.

Fig. 8 is a similar elevation of such parts, viewed in the direction of arrow 8 in Fig. 6.

Fig. 9 is a fragmentary view, being a section on the line 9—9 in Fig. 6.

Fig. 10 is a sectional detail of Fig. 5, the parts

55 being in the wave bending position.

Fig. 11 is an elevation of the parts shown in Fig. 10.

Fig. 12 is a detailed elevation of the ejecting means shown at the left in Fig. 4.

Figs. 5 to 12 inclusive are on the same scale as Figs. 3 and 4.

Fig. 13 is an elevation of the cam for operating the wave rolling or roll advancing toggles, being on the same scale as Fig. 2 and looking in the direction of arrow 13 therein. The same cam is shown in dotted lines in Fig. 3.

The parts of the present machine corresponding to those set forth in my aforesaid application will first be identified.

With respect to any one of the multiple units of the machine, the inner roll (i. e., the roll operating inside the can body) is shown at 2 mounted on its shaft or mandrel 3, and the outer rolls are shown at 4 and 5, being mounted on a movable carrying part whereby they move together toward or from the inner roll 2.

The can body B to be treated is received between end guides 34, 35 at its opposite ends, which serve to prevent its longitudinal displacement during the operation of the wave bending rolls, and also in the present construction are utilized as the means for feeding the can body to and from the working position.

In the multiple machine these parts pertaining to a single unit are mounted on rotary carriers 30 and caused to revolve around a fixed axis, which is preferably horizontal. In the construction shown this axis is constituted by a stationary shaft H which is supported on pedestals I, I projecting from a base or table J, which may be elevated on legs K, K. In fixed relation with the shaft are two stationary cams L and M. The cam L is a grooved disk fixed to a stationary gear N, which is keyed to the shaft. Around its periphery, in mesh with its teeth are planet pinions 35 a, c, which are fixed on the ends of the inner spindles 3, 3 of the respective units. In the machine illustrated there are eight of these units. The eight spindles 3, 3 are carried in bearings b, b, fastened to a revolving carrier P, which is mounted to turn freely on the shaft H. The carrier P is fixedly connected to a carrier Q in the form of a hollow shell having its hub c mounted to turn freely on the shaft H. For driving the carriers Q and P, a gear wheel d fixed on the hub c is engaged by a pinion e on a driving shaft f, on which, outside the bearing I', is a pulley g or other means of applying power, controlled by a lever g' which may apply a clutch. The fixed connection between the carriers P and Q is best

40 45 50 55

connection between the carriers P and Q is best 55

55

shown in Fig. 5. The carrier Q is shown as 2, 4, 5; and subsequently at the end of the wave bending operation the cam groove 112 imparts 5 to the treated can body is fed out from between the rolls 2, 4, 5 into position for feeding out from the machine.

The carrier P carries the wave forming rolls 2, 4, 5, while the carrier Q carries the means for feeding the can bodies to the rolls, guiding them during the wave rolling operation and removing them therefrom preliminary to their being ejected from the machine.

For the mounting of the movable rolls 4, 5 of the respective units, the carrier P is formed on its opposite ends with radial slots or slideways m, m, best shown in Figs. 4 and 6, in which move slides n, n, best shown in Figs. 4, 6, 7 and 8. The rolls 4, 5 are shown as tubular rolls having roller bearing mountings on pins o, o of each unit are fastened at their opposite ends in the two slides n, n of that unit, as best shown in Figs. 6, 7 and 8.

The two slides n, n are moved radially outward and inward together. Their outward movement brings the rolls 4, 5 into operative engagement with the inner roll 2 for performing the wave rolling operation, as best shown in Fig. 3 at the right hand and lower part of the figure; their inward movement carries the rolls away from the inner roll 2, as shown at the left and upper part in Fig. 3. These movements are imparted to the guides n, n by toggle connections under control of the sinuous cam groove p of the cam L. This groove is traversed by rollers q, q carried on arms r, t (one for each unit), each arm being mounted fixedly on one end of a rock shaft s having bearings in the carrier P. On this shaft are fixed two toggle arms t, t at opposite ends, jointed to toggle links u, u, as shown in Figs. 7 and 8, these links having pin connections with the slides n, n. Thus, as the cam groove moves the rollers out or in, the spindles s are rocked and the toggles t, u, straightened or buckled to force the slides outward or draw them inward and thereby control the co-action of the wave forming rolls. For the adjustment of the toggles t, u whereby to control the throw of the slides n, n the roller carrying arm r is shown as provided with adjusting screws v, v (Figs. 7 and 9) which engage the side of the toggle arm t so that the angular relation of the lever arms r and t may be varied and thereby the toggles brought more or less nearly to their straight relation in the active positions of the rolls 4, 5.

The can body guides 34, 35 of each unit are carried on sliding rods w, w, best shown in Figs. 3 and 5, which rods are mounted in pairs with a crosshead y connecting them which carries a roller z which rolls in the cam groove 112 of the drum cam M. Each rod w is prolonged at w'. The pairs of rods w slide through guiding holes 113 formed in bosses 114 on the shell of the rotary carrier Q; and their portions w' slide through bores 115, formed in bosses on the right hand end of the shell portion i and in the end disk h where these members of the carrier Q join, as shown at the right in Figs. 2 and 5.

As the carriers P and Q revolve they carry the rollers q and z around in the grooves of the respective cams L and M. The groove 112 in the cam M, acting on the rollers z moves the rods w and the can body guides 34, 35 carried by them for carrying the fed in can bodies into working position between the wave bending rolls

2, 4, 5; and subsequently at the end of the wave bending operation the cam groove 112 imparts a return movement to these rods and guides whereby the treated can body is fed out from between the rolls 2, 4, 5 into position for feeding out from the machine.

For feeding the can bodies to be treated into the machine, they are delivered by any suitable known can body handling means into a chute or reservoir R, which is shown in Fig. 1 as mounted in stationary and preferably inclined position at the upper part of the machine. The can bodies B, B descend through this feeding chute, the lowermost one dropping to the position shown in Fig. 3, where it is arrested by any suitable part, this function being conveniently performed by the hubs 116, 117, on which are mounted the guides 34, 35, which have concave faces 119 to receive the can body. The rotary carriers turn in the direction of the arrows x' in Figs. 1, 3 and 4. During this rotation the can bodies are carried around circumferentially from the entering position under the chute R to a delivering position, where they are dropped into a delivery chute S having an inclined bottom 118, down which they roll and are discharged out from the machine.

As each can body is delivered into the machine at the foot of the chute R it enters through the rotation of the carriers between the two can body guides 34 and 35 which are aligned with its opposite ends, as shown in Fig. 2. These guides are relatively adjustable to adapt them to the length of the particular can body to be treated, and are made slightly self-adjusting by the yielding of a spring 120 (Fig. 11) tending to draw them together, with a screw pin 121 for limiting their approach, these parts being applied to the hubs 116, 117, one of which is keyed on the rod w, and the other has a sliding connection with a spline 122 (Fig. 10) to prevent rotative displacement. The movable guide 34 has a lug 123 which is engaged by a projection 124 (Figs. 5 and 10) forming an abutment stop so that in the retracted or feeding-in position the lug abuts the projection and is thereby stopped to hold the guides 34, 35 sufficiently apart to permit the can bodies to fall freely in between them. The same condition occurs in the feeding out position, so that the treated can body may freely drop out from between the guides.

The guides 34, 35 for each can body are preferably divided into two sections, as shown best in Fig. 3, each section being mounted on its own rod w so that by the simultaneous movement of the twin rods the two sections move as one. They are shaped, as best shown at the top of Fig. 3, to engage the end of the can body B, while the open space between them is sufficiently large to keep them free from the internal roll 2 when the guides are advanced to feed the can body onto this roll. To hold the respective guide sections in their proper angular positions each is keyed, splined, or otherwise non-rotatively mounted (as above described) on its rod w, and the two rods w are keyed or otherwise non-rotatively engaged with their common head y.

Shortly after each can body is received between the guides 34, 35, these guides are advanced by the operation of the cam groove 112, whereby the body is displaced endwise for a distance exceeding its length and carried onto the internal roll 2 and between this and the external rolls 4 and 5. This movement is completed about the time the can body reaches the position shown at B' in Fig. 3. Shortly after

feeding the can body thus over the inner roll the outer rolls are advanced in the manner already described through the action of the cam L to bring these rolls into working engagement 5 with the inner roll 2, as shown at the right in position B³ in Fig. 3. While moving past the position B³ and to a point between the positions B⁴ and B⁵ the wave bending operation of the respective rolls is performed; that is to say, the 10 external rolls force the sheet metal of the can body against the yielding surface of the internal roll with sufficient pressure to cause the sheet metal to penetrate into the cushion formed by the yielding surface portion of the internal roll, thereby forming two concave wave portions 15 in the sheet metal with an intervening convex wave portion, as shown in Fig. 3 at positions B³ and B⁴. Since the internal roll is revolving, it carries the can body around with it so that 20 this wave bending action progresses circumferentially around the can body; and this is performed for one or more revolutions, sufficient to accomplish the requisite wave bending operation 25 in the manner described in the pending application hereinabove referred to. When a sufficient duration of wave bending has thus been performed the external rolls 4, 5 are moved back slightly so that they no longer force the sheet metal of the can body to penetrate the cushioning surface of the internal roll, this being the 30 condition shown at B⁵ and B⁶ in Fig. 3. In this position of the external rolls their pressure against the can body and internal roll is just sufficient to roll out any residual waves that may 35 be left in the can body at the termination of the wave bending operation; thereby smoothly rounding the can body and bringing it into its final perfected form, ready for delivery out from the machine.

40 For ejecting the treated can bodies after the return movement of the guides 34, 35 has fed them out from between the respective rolls, to insure their falling in correct time into the delivery chute S, a series of ejecting levers T are 45 provided, one for each unit. These levers are pivoted, as shown in Fig. 4, on the rods w, and are formed with two arms, the one carrying a pin 130, and the other projecting outwardly so as in the ejecting position to encounter a roller cam 131 (Fig. 4) whereby the lever is rocked so that its pin 130 which projects between the 50 can body B and the inner shell j exerts an outward thrust against the can body, thereby throwing it into the chute S. The levers T, T are retracted by springs 132, shown in Figs. 4 and 12. In their retracted position the pins extend inward 55 closely adjacent to the inner shell j where they lie slightly beyond the feeding-in position of the entering can bodies.

60 For the proper support of the infeeding chute R and the outfeeding chute S, a fixed frame U is provided, shown as in the form of an arch, with its feet bolted to the base J. This frame carries 65 adjustable rods 135, 135, on which are adjustably fastened the side walls 136 of the chute R, which also has guide strips 137 adjustably fastened within these walls, the construction thus being such as to admit of the chute R being varied in 70 dimensions for any size can body to be treated. To prevent any possible misplacement of the can bodies in a rapidly moving machine, a guard plate 140 is provided in the position shown in Figs. 2 and 3, being conveniently supported by bolting to a rod 141 clamped by a set screw 142 to a collar 75

143 which is fastened by set screws on one of the rods 135.

The delivery chute S is supported by being provided with brackets 145 (Fig. 1) adjustably fastened by bolts to the foot portion of the frame U. An apron V is desirably provided beneath the units in their active positions, as shown in Figs. 1, 2 and 3, being supported by a bracket 146 bolted adjustably to the base J.

The multiple unit machine thus described is 10 capable of continuous operation at a high rate of speed, receiving the can bodies continuously from the feed chute and ejecting them in rapid succession for delivery through the outgoing chute. The method performed by the machine is precisely 15 that set forth in the aforesaid application, Serial No. 628,339, and the rolls or rollers for performing the wave bending may be of any of the kinds therein described. The only essential is that in their rotary progress the respective internal and external rolls move together into operative relation, the preferable way of accomplishing this being to mount the internal rolls on spindles in fixed bearings relative to the carrier P and to make the spindles carrying the external 20 rolls radially movable during the angular progression of the units due to the rotation of their carriers. The arrangement of the bending rolls with their axes parallel on an essentially drum-shaped carrier as herein shown is the preferable 25 arrangement. It will be understood that the combination of the wave rolling units into a multiple unit machine as herein shown and described is capable of variation in arrangement and in structural details and in mechanical expedients for 30 communicating motion to the parts, all within the scope of the discretion of the engineering designer.

While the machine as herein described is for the treatment of can bodies, it is to be remarked 40 that such bodies are essentially sheet metal tubes, the machine being applicable to the rounding and the truing of other such tubes or similar sheet metal articles, it being understood that any forms of tubular sheet metal articles are included in the 45 term "can bodies" as herein used.

I claim:

1. A machine for treating can bodies comprising a plurality of units each consisting of internal and external wave-bending rolls, for engaging 50 the sheet metal body between them, with means for rotating them to act circumferentially on the body, with rotative carrying means for such units, and means comprising opposite guides engaging the body between them, movable to feed successive bodies between the rolls for treatment and to remove the treated bodies from between the rolls.

2. A machine according to claim 1, with a stationary cam, and means moving with the units, 60 engaged by said cam and actuating said feeding means.

3. A machine according to claim 1, the said guides relatively movable, with means for separating them in the feeding in or out positions and closing them together to embrace the body in the intermediate positions.

4. A machine according to claim 1, one of said guides movable toward or from the other, a spring 70 drawing them together, and a fixed abutment engaging such movable guide to separate the guides to free the body.

5. A machine according to claim 1, said guides having carrying means sliding parallel with the 75

roll axes for pushing the bodies into working position.

6. A machine for forming smoothly rounded can bodies comprising a plurality of units each consisting of internal and external revolving wave-bending rolls, adapted to receive the sheet metal body between them and to roll the body circumferentially under pressure sufficient to flex it and stress it beyond its elastic limit, with means for driving the rolls, and means for introducing the bodies between the rolls of successive units for treatment by displacing them for their entire length and for removing the treated bodies by oppositely displacing them beyond the rolls, the means for introducing the bodies between the rolls comprising guides and carrying means therefor sliding parallel with the roll axes for pushing the bodies into working position, said carrying means for each unit having a roller, 10 and a stationary cam engaging said rollers for imparting longitudinal movements to said carrying means.

7. A machine for forming smoothly rounded can bodies comprising a plurality of units each consisting of internal and external revolving wave-bending rolls, adapted to receive the sheet metal body between them and to roll the body circumferentially under pressure sufficient to flex it and stress it beyond its elastic limit, with means for driving the rolls, and means for introducing the bodies between the rolls of successive units for treatment by displacing them for their entire length and for removing the treated bodies by oppositely displacing them beyond the rolls, the internal and external rolls being relatively movable by means of movable carrying parts on which at least one of such rolls for each unit is mounted, and toggle means being provided to engage such carrying parts for imparting to them the respective movements, stationary actuating means being also provided to operate such toggle means for imparting said movements.

8. A machine for forming smoothly rounded can bodies comprising a plurality of units each consisting of internal and external revolving wave-bending rolls, adapted to receive the sheet metal body between them and to roll the body circumferentially under pressure sufficient to flex it and stress it beyond its elastic limit, with means for driving the rolls, and means for introducing the bodies between the rolls of successive units for treatment by displacing them for their entire length and for removing the treated bodies by oppositely displacing them beyond the rolls, the machine having a stationary shaft, fixed frames supporting it, a carrying means for the units, rotatively mounted on said shaft and including a shell portion, reciprocating members

for introducing the can body between the rolls, and a stationary cam fixedly mounted on said shaft for reciprocating said members, said shell portion forming a bearing support for said reciprocating members and enclosing said stationary cam within it.

9. A machine for treating tubular can bodies with open ends for bringing them to smoothly rounded form, comprising a plurality of units, each consisting of an internal revolving roll and at least one external revolving roll adapted to receive the sheet metal body between them, and on being forced together to roll the body circumferentially under pressure to flex and stretch it beyond its elastic limit, with means for driving the rolls, means for successively feeding the bodies between the rolls of successive units by displacing the bodies endwise in a direction parallel to the axes of the rolls for a distance equal to their entire length, means for thereafter forcing the rolls together to so roll the body between them, means for then separating the rolls, and means for feeding off the treated bodies by oppositely displacing them endwise to carry them beyond the rolls, the means for feeding and removing the bodies comprising guide plates for acting against opposite ends of a body, and means for moving said plates in one direction for feeding on and in the opposite direction for feeding off, each such movement exceeding the length of the body.

10. A machine for treating tubular can bodies with open ends for bringing them to smoothly rounded form, comprising a plurality of units, each consisting of an internal revolving roll and at least one external revolving roll adapted to receive the sheet metal body between them, and on being forced together to roll the body circumferentially under pressure to flex and stretch it beyond its elastic limit, with means for driving the rolls, means for successively feeding the bodies between the rolls of successive units by displacing the bodies endwise in a direction parallel to the axes of the rolls for a distance equal to their entire length, means for thereafter forcing the rolls together to so roll the body between them, means for then separating the rolls, and means for feeding off the treated bodies by oppositely displacing them endwise to carry them beyond the rolls, the means for feeding and removing the bodies comprising guide plates for acting against opposite ends of a body, supporting means for each pair of guide plates comprising a slide carrying said plates, and means for successively moving said slides in one direction for feeding on bodies and in the opposite direction for feeding off.

FRANK KRUEGER.
